UNITED STATES PATENT OFFICE.

WILLIAM W. WYTHE AND WILLIAM H. WYTHE, OF ORANGE, NEW JERSEY,
ASSIGNORS TO THE NATIONAL CASH REGISTER COMPANY, OF DAYTON,
OHIO.

CASH INDICATOR AND RECORDER.

SPECIFICATION forming part of Letters Patent No. 606,324, dated June 28, 1898.

Application filed October 26, 1892. Serial No. 450,033. (No model.)

To all whom it may concern:

Be it known that we, WILLIAM W. WYTHE and WILLIAM H. WYTHE, citizens of the United States, residing at Orange, in the county of Essex and State of New Jersey, have invented certain new and useful Improvements in Cash Indicators and Recorders, of which the following is a description, reference being had to the accompanying drawings, forming part of this specification.

Our invention relates to that class of machines in which an indicating-dial is employed to indicate the amounts of the different sales and in which a printing device is employed to print said amounts upon a record-strip carried within the machine. Its novelty consists in new combinations, arrangements, modes of operation, and mechanical constructions of the various parts employed, all as will be hereinafter set forth, and particularly pointed out in the claims.

In the accompanying drawings, Figure 1 represents a front elevation of our improved machine with a portion of the front plate of the casing broken away to expose the dial; Fig. 2, a front elevation of the machine with the front plate of the casing and the dial removed, showing the drawer-compartment and drawer in section; Fig. 3, a vertical section through the middle of the casing and drawer-compartment, but showing the working parts of the machine in elevation; and Fig. 4, a horizontal section approximately on the line 4-4 of Fig. 2.

The same numbers and letters of reference are used to indicate identical parts in all the figures.

The casing of the machine, which incloses the working parts, is mounted upon a base A, which contains a drawer-compartment, having fitted in it a sliding money-drawer B, which is locked in its closed position by means hereinafter described, and is automatically thrown open, when unlocked, by the action of a coiled spring C, which is connected at its forward end to the base of the machine and at its rear end to a lever D, Figs. 2 and 3, which is pivoted at one end in a slotted lug E, secured to the base, and carries at its opposite end a friction-roller which bears against a plate F upon the under side of the

drawer. The shape of the casing is shown in the horizontal section in Fig. 4, where it will be seen that it consists of a narrow front portion extending transversely across the base and composed of a front plate G and a back-plate H, having the side plates I integral with it, and a rearwardly-extending portion J, located at right angles to the front portion and communicating with the latter through an opening 11 at its lower forward corner, Figs. 2, 3, and 4.

Journaled in the front and back plates G II of the forward portion of the casing is a shaft 2, having fast upon its front end, outside the casing, an operating-handle 3 and a pointer 4, adapted, when the handle and shaft are turned, to travel over a series of numbers arranged in a circle upon the face of the front plate G, Fig. 1. Fast upon the shaft 2, immediately in rear of the front plate G, is a circular dial 5, bearing a series of indicating-numbers arranged in a circle around its edge and adapted to be exposed singly through a glass-covered window or sight-opening 6 in the front plate of the casing. The numbers upon the dial correspond to those upon the front plate over which the pointer 4 travels, and the adjustment of the parts is such that whenever the operating-handle is turned until the pointer is brought over a given number the corresponding number upon the dial will be brought opposite the sight-opening 6. Thus, to make an indication, the operator grasps the knob of the handle 3 and turns the shaft until the pointer is brought to the desired number.

Fast upon the shaft 2 in rear of the dial is a type-wheel 7, bearing in relief a series of type-numbers corresponding to those upon the dial and front plate of the casing, and this type-wheel is secured upon the shaft in such position that whenever a given number upon the dial is brought opposite the sight-opening 6 the corresponding number upon the type-wheel will be brought opposite the printing-point, hereinafter described. Fast upon the shaft 2, between the dial and type-wheel, is a disk 41, having a series of depressions in its periphery with which cooperates a roller 42 upon the end of a lever 42^a, pivoted to the casing and having connected

to it a spring 42^b, which yieldingly presses the roller 42 against the disk 41. The depressions in the disk 41 correspond to the indicating and type numbers, and whenever 5 a given number is brought to the indicating and printing points the engagement of the roller 42 with one of the depressions in the disk 41 yieldingly holds the parts in proper position.

10 Carried upon a shaft S, mounted at its ends in the side plates of the rearwardly-extending portion J of the casing, Fig. 3, is a ratchet-wheel 8, having a hub 9 and a flange or drum 19 secured to it. This ratchet-wheel may be 15 either loose upon the shaft S or be fast upon it and the latter be free to revolve. Loosely mounted upon the hub 9 of the ratchet-wheel and free to be unwound therefrom is a roll-of-paper record-strip 10, which is led forward 20 beneath a guide-rod 12, Fig. 3, thence over said rod to the right around a roller 13, Fig. 2, thence upward over a roller 14 and a platen 15, carried by a printing-lever 20, thence over a roller 16 on said lever and downward around 25 a roller 17, thence to the left beneath a guide-rod 18, and thence over said rod and to the rear around the drum 19 on the ratchet-wheel 8, Fig. 3. The ratchet-wheel is turned step by step at each operation of the machine by 30 the means hereinafter described to draw the record-strip from its supply-roll past the printing-point and wind it upon the drum 19.

The printing-lever 20 is actuated at each operation of the machine to effect the printing 35 by means of a three-armed lever 45, pivoted at K to a support L, projecting forward from the wall II of the casing, Fig. 3. The horizontal arm 25 of this lever has pivoted to it a trip 26, which co-operates with the arm 28 40 of the printing-lever 20. When the lever 45 is rocked so that its arm 25 is thrown upward, the trip 26 will lift the arm 28 of the printing-lever 20, being prevented from yielding in that direction by a pin 27, and will 45 move the upper end of said lever and the platen 15 to the right against the pressure of a spring 22, which bears against said lever, and when the trip 26 has cleared the end of the arm 28 the spring 22 will throw the lever 50 20 to the left, and the momentum thus imparted to the printing-lever will cause the platen 15 to carry the record-strip against the type-number which is then at the printing-point and print such number upon the 55 strip. A counterweight 21, secured to an arm of the lever 20 opposite the arm 28, returns the lever and platen to normal position after the printing has been effected by the action of the spring 22 and yieldingly holds them in 60 such position. When the lever 45 is returned to initial position and its arm 25 thrown downward again, the beveled end of the trip 26 will ride over the end of the arm 28 and re-engage the latter when it has passed below 65 it, a spring bearing against the under side of the trip operating to reset it.

The types upon the type-wheel 7 are inked

after they have been brought to the printing-point by an inking-roller 32, carried in supports hung to an arm 31, loose upon the shaft 70 2. A pin 33 projects from the rear side of the arm 31 near its upper end, and the engagement of this pin with the upper end of the printing-lever 20 holds the arm 31 in normal position with the inking-roller above the 75 printing-point and out of the way of the platen, but when the upper end of the printing-lever 20 is thrown to the right in the manner above described the arm 31 is released and the roller 32 travels downward until the 80 pin 33 strikes a pin 34, projecting from the lever 20. The travel thus permitted the arm 31 is sufficient to carry the roller 32 over the type-number, which has been brought to the printing-point and cause it to ink the type. 85 When the printing-lever 20 is thrown to the left again by the spring 22, as heretofore described, the engagement of the upper end of the lever with the pin 33 will carry the arm 31 and inking-roller back to initial position 90 and out of the path of the platen 15.

The lever 45 has an operating-handle 29, secured to the lower end of its curved lower arm 24 and projecting out through a slot in the front wall of the casing, and at each operation of the machine this handle 29 is thrown to the right by the clerk or operator to oscillate the lever 45 and effect the printing, and when the handle is released it and the lever 45 are reset by a spring 30, connected to the 100 lower end of the lever. This movement of the handle 29 will also cause the ratchet-wheel 8 to be turned to wind up the record-strip upon the drum 19 by means of a pawl 37, pivoted to the rear end of a sliding rod 105 36, Figs. 3 and 4, whose front end is pivoted to the left-hand end of an arm 35, Fig. 4, whose right-hand end is pivoted in a support on the rear wall II of the casing and which has at its left-hand end a projecting portion 110 35^a, which presents an inclined beveled surface to a lug 38 upon the upper edge of the arm 24 of the lever 45. When this end of the lever is thrown to the right by the handle 29, the lug 38 will engage the projection 35^a and 115 force the left-hand end of said arm and the sliding rod 36 to the rear and cause the pawl 35 to turn the ratchet-wheel 8. When the handle 29 is released and reset by the spring 30, the arm 35 and rod 36 will be reset by a 120 coiled spring 39, which surrounds the rod 36 and is confined between its fixed guide 40 and a shoulder upon the rod, Fig. 3. In this manner each time the handle 29 is thrown to the right the ratchet-wheel 8 will be turned 125 to bring a blank portion of the record-strip to the printing-point, while the arm 25 of the lever 45 is retracting the printing-lever preparatory to the printing, and the adjustment of the parts is such that the printing-lever 130 will be released and thrown to the left by the spring 22 to effect the printing before the stroke of the handle 29 to the right is completed, so that the ratchet-wheel will be

moved to advance the record-strip before the printing is effected.

From the foregoing description it will be understood that the operation of this much of the machine consists in turning the operating-handle 3 until the pointer 4 is brought to the desired number upon the front plate of the casing and then throwing the handle 29 to the right. The turning of the pointer 4 to the number on the casing will bring the corresponding number on the dial to a position opposite the sight-opening 6 and the same number upon the type-wheel to the printing-point, while the movement of the handle 29 will advance the record-strip and cause the amount indicated by the dial to be printed upon said strip.

The lever 42^a, which carries the roller 42, co-operating with the disk 41, is provided at its left-hand end with a hook 43, which co-operates with a lug 44 upon the lever 45. When the roller 42 is resting in one of the depressions in the disk 41, the spring 42^b holds the hook above the lug 44; but whenever the roller 42 rests upon one of the raised spaces between two of the depressions in the disk 41 the hook 43 is thrown downward over the lug 44 and in such position locks the lever 45 from movement. This necessitates the moving of the pointer 4 to a position exactly opposite some one of the numbers on the casing, and consequently the bringing of the corresponding numbers upon the dial and type-wheel to exact indicating and printing positions before the handle 29 can be moved to advance the record-strip and effect the printing.

Mounted upon the wall H of the casing is a gong 49^a, arranged to be sounded by a striker 49, pivoted to said wall and actuated by a pin 48 on the arm 24 of the lever 45. When the handle 29 is thrown to the right, the pin 48 will raise the striker, and when the handle is released and reset by the spring 30 the striker will drop against the gong and sound it.

The money-drawer B is held in its closed position by a latch-arm 47, Fig. 4, which is provided near its front end with a notch co-operating with a catch-plate 47^a upon the drawer, a spring 47^b yieldingly holding the latch-plate in locking position. A short distance from its front end the latch-arm 47 has secured to or formed upon it an upwardly-projecting arm 47^c, which extends through a slot in the top of the base A into position to be engaged by the right-hand end of an arm 46, Figs. 2 and 4, which is pivoted to the lower arm 24 of the lever 45. Whenever the handle 29 is thrown to the right, as before described, the arm 46 will carry the latch-arm 47 to the right and disengage it from the catch-plate upon the drawer and release the latter, whereupon the drawer will be thrown open by the spring C, heretofore described. When the drawer is pushed in again, the plate 47^a will reengage the notch in the latch 47 and the drawer become relocked.

It is desirable in machines of this class to provide means for hiding the numbers upon the indicating-dial while the latter is being moved to effect a new indication, and we have devised a novel automatic screen for that purpose. As shown by the dotted lines in Fig. 1, there are loosely mounted upon the shaft 2, between the front plate G and the dial 5, two sector-plates 51 and 52, projecting beyond the edge of the dial and adapted to be oscillated back and forth behind the sight-opening 6. Each of these plates has secured to its rear side, near its upper end, a spring 53, Fig. 3, which bears at its lower end against the rear side of the dial or carries a friction-block which bears against the dial. These springs form a frictional connection between the plates and the dial, and cause the dial to carry the plates with it in either direction in which it is moved, so far as the limit of movement of the plates will permit. The two plates overlap each other adjacent to the shaft 2, but are held apart at their outer ends by a projection 55 upon the plate 52, Fig. 1. In the latter figure the plate 52 is in approximately its extreme right-hand position and the plate 51 in its right-hand position immediately behind the sight-opening 6. The two plates are capable of movement toward the left far enough to bring the plate 52 into the position occupied by the plate 51 in Fig. 1 and carry the latter to the left of the sight-opening, the plates being limited in their movements by engagement with the side plates I of the casing. The plate 51 has upon its rear side a pin 54, which projects into the path of travel of the upper end of the lever 45, Fig. 2, and when that end of the lever is thrown to the left by the movement of the handle 29 to the right it will carry the plate 51 with it and expose to view the number upon the dial, which is at that time behind the opening 6. Thus in Fig. 1, if the operating-handle 3 be turned until the pointer 4 is brought to the number "15" on the front plate of the casing, the number "15" upon the dial will be brought opposite the opening 6, but will remain hidden by the plate 51. Upon throwing the handle 29 to the right, however, to effect the printing and to open the cash-drawer, the upper end of the lever 45 will carry the plate 51 to the left and expose the number "15" at the opening 6. If the operating-handle be now turned backward, the screen-plate 52 will be carried to the left by the dial and brought behind the sight-opening 6. There is no means provided for moving the plate 52 to the right again except by turning the dial in that direction, and this will carry the screen 51 to the right and bring it behind the sight-opening, where it will remain until the handle 29 is moved to the right again, as before described. It will thus be seen that in making a new indication the operating-handle and dial must always be turned to the right or clockwise, for if turned in the opposite direction the plate 52 will be carried behind the sight-opening.

and hide the numbers upon the dial, and the latter must then be turned to the right in order to get the plate 52 away from the sight-opening. Thus in Fig. 1, with the pointer 5 and dial at the number "3," if the next amount to be indicated and recorded should be ninety the handle and dial must be given nearly a complete revolution to the right and the pointer brought to the number "90," 70 whereupon the plate 51 can be turned to the left by operating the handle 29 and the number "90" on the dial be exposed at the opening 6, whereas if it be attempted to indicate said number by simply turning the handle to the 75 left until the pointer 4 is brought opposite the number "90" the plate 52 will be carried behind the opening 6 and hide the number on the dial.

From the foregoing description it will be 80 understood that at the end of each operation of the machine the screen-plates 51 and 52 stand upon opposite sides of the sight-opening 6, and that to make a new indication the handle and parts moved by it must be turned 85 to the right and the plate 51 be carried behind the sight-opening and the plates 51 be then thrown to the left again to expose the new number on the dial. By providing the shaft 2 with a ratchet and coöperating pawl, 90 which would prevent backward movement of the shaft and always compel it to be turned to the right or clockwise, the plate 52 might be dispensed with, for after an indication had been made in the manner before described, 95 the plate 51 would always be carried to the right behind the sight-opening at the beginning of the forward movement of the handle and dial and remain there until thrown to the left again by the operation of the handle 100 29. On the other hand, if the machine were provided with means to compel the handle and dial to be moved backward to initial position before a new indication could be made, as are some machines of this class, the plate 105 51 might be dispensed with and the plate 52 be employed alone and operated solely by its frictional connection with the dial. In such case it would be carried to the left behind the sight-opening at the beginning of the backward movement of the handle and dial, and would be carried to the right again as they 110 were moved forward from initial position, as will be readily understood; but in such case while the numbers upon the dial would be hidden by the plate during the backward movement of the dial they would be exposed to view during its forward movement.

As far as we are aware we are the first in 115 the art to provide either a rotary or an oscillatory indicating-dial with a screen-plate operated either wholly or in part by a frictional connection with said dial, and we desire to secure such combination as our invention whether it be employed in a machine in which it is necessary to return the dial to initial position at each operation or in a machine in 120 which such return is unnecessary.

So far as we are aware, also, we are the first in the art to combine a shaft, either oscillatory or rotary, an indicating-dial and a type-wheel fast upon the shaft, a platen coöperating with the type-wheel, a feeding mechanism for moving the record-strip past the printing-point, and a single operating-handle so connected to the feeding mechanism and platen 125 as to advance the record-strip and effect the printing, as well as the first to produce the several other combinations recited in our claims, and our invention in these respects is not limited further than the terms of our 130 claims imply.

Having thus fully described our invention, we claim—

1. In a cash indicator and recorder, the combination of a shaft, an indicating-dial and a type-wheel fast thereon side by side, the indicating-dial being provided on its face with a series of indicating-numbers exposable singly through a sight-opening in the casing, and the type-wheel being provided with a series of type-numbers on its periphery, a platen coöperating with the type-wheel, feeding mechanism for moving the record-strip past the printing-point, an operating-handle, and connections between said handle and the feeding mechanism and platen, to advance the record-strip and effect the printing by the operation of said handle. 140

2. In a cash indicator and recorder, the combination of a shaft, an indicating-dial and a type-wheel fast thereon, a platen coöperating with the type-wheel, an automatically-opening cash-drawer, a lock for holding the same closed, an operating-handle independent of the drawer, and connections between said 145 handle and the platen and drawer-lock, for effecting the printing and releasing the drawer by the operation of said handle.

3. In a cash indicator and recorder, the combination of a casing having a sight-opening shaft, an indicating-dial fast thereon and provided upon its face with a series of indicating-numbers exposable singly at the sight-opening in the casing, a type-wheel also fast upon said shaft and provided with a series of 150 type-numbers on its periphery, a platen coöperating with the type-wheel, feeding mechanism for moving the record-strip past the printing-point, a cash-drawer, a lock therefor, an operating-handle, and connections between said handle and the feeding mechanism, platen and drawer-lock, for advancing the record-strip, effecting the printing and releasing the drawer by the operation of said handle. 155

4. In a cash indicator and recorder, the combination of a shaft, an indicating-dial and a type-wheel fast thereon, a platen coöperating with the type-wheel, feeding mechanism for moving the record-strip past the printing-point, an automatically-opening cash-drawer, a lock therefor, a gong, a striker therefor, an operating-handle independent of the cash-drawer, and connections between said handle 160

and the feeding mechanism, platen, drawer-lock and gong-striker, for advancing the record-strip, effecting the printing, releasing the drawer and sounding the gong by the operation of said handle.

5. In a cash indicator and recorder, the combination of a shaft, an indicating-dial and a type-wheel fast side by side thereon, a spring-actuated platen coöperating with the type-wheel, feeding mechanism for advancing the record-strip, an operating-lever, and connections between said lever and the feeding mechanism and platen, for advancing the record-strip and retracting the platen to effect the printing by the positive stroke of said lever.

6. In a cash indicator and recorder, the combination of a shaft, an indicating-dial and a type-wheel fast thereon, a spring-actuated platen coöperating with the type-wheel, feeding mechanism for moving the record-strip past the printing-point, an automatically-opening cash-drawer, a lock therefor, an operating-lever independent of the drawer, and actuating connections between said lever and the feeding mechanism, platen, and drawer-lock, for the purpose described.

7. In a cash-indicator, the combination of a casing provided with a sight-opening, an indicating-dial adapted to expose its numbers singly at said opening, an oscillatory screen-plate interposed between said dial and sight-opening and frictionally connected with the dial so as to be moved by the latter, and means for limiting the movement of the screen-plate, for the purpose described.

8. In a cash-indicator, the combination of a casing having a sight-opening, an indicating-dial adapted to expose its numbers singly at said opening, an oscillatory screen-plate interposed between said dial and sight-opening and frictionally connected with the dial, and means for moving the screen-plate in one direction independently of the dial, for the purpose specified.

45. 9. In a cash-indicator, the combination of a casing provided with a sight-opening, an indicating-dial adapted to expose its numbers singly at said opening, an oscillatory screen-plate loosely mounted on the axis of said dial and frictionally connected with the dial so as to be moved by the latter, and means for limiting the movement of the screen-plate, for the purpose described.

10. In a cash-indicator the combination of a casing having a sight-opening, an indicating-dial adapted to expose its numbers singly at said opening, an oscillatory screen-plate interposed between said dial and sight-opening and frictionally connected with the dial, a cash-drawer, a lock therefor, an operating-handle, and connections between said handle and the drawer-lock and screen-plate, for releasing the drawer and moving the screen-plate away from the sight-opening by the operation of said handle.

65. 11. In a cash-indicator having a casing provided with a sight-opening, the combination

of a shaft, an indicating-dial and a type-wheel fast thereon, an oscillatory screen-plate loose thereon and frictionally connected with the dial, a platen coöperating with the type-wheel, an operating-handle, and connections between said handle and the platen and screen-plate, for effecting the printing and moving the screen-plate away from the sight-opening by the operation of said handle.

12. In a cash indicator and recorder having a casing provided with a sight-opening, the combination of a shaft, an indicating-dial and a type-wheel fast thereon, an oscillatory screen-plate loose thereon and frictionally connected with the dial, a platen coöperating with the type-wheel, feeding mechanism for moving a record-strip past the printing-point, an operating-handle, and connections between said handle and the feeding mechanism, platen and screen-plate, for the purpose described.

13. In a cash indicator and recorder having a casing provided with a sight-opening, the combination of a shaft, an indicating-dial and a type-wheel fast thereon, an oscillatory screen-plate loose thereon and frictionally connected with the dial, a platen coöperating with the type-wheel, feeding mechanism for moving a record-strip past the printing-point, a cash-drawer, a lock therefor, an operating-handle, and connections between said handle and the feeding mechanism, platen, drawer-lock and screen-plate, for the purpose described.

14. In a cash-recorder, the combination of an adjustable type-wheel, a platen coöperating therewith, an operating-handle, connections between the same and the platen for actuating the latter, and a lock for said handle controlled by the position of the type-wheel and controlling the positive movement of said handle to prevent operation of the handle except when the type-wheel is in proper position to coöperate with the platen.

15. In a cash-indicator, the combination of a casing having a sight-opening, an indicating-dial adapted to expose its numbers singly at said opening, an oscillating screen-plate coöperating with the dial to alternately hide and expose its numbers at said opening, an operating-handle, connections between the handle and screen-plate for moving the latter away from the sight-opening, and a lock for the handle controlled by the position of the indicating-dial, to prevent operation of the handle except when one of the numbers upon the dial is in proper position behind the sight-opening.

16. In a cash indicator and recorder, the combination of an indicating-dial and a type-wheel moving together, an oscillating screen-plate coöperating with the dial and a platen coöperating with the type-wheel, an operating-handle, connections between the same and the screen-plate and platen for actuating the former to expose the number upon the dial and the latter to effect its printing by

the type-wheel, and a lock for said handle controlled by the position of the dial and type-wheel, to prevent operation of said handle except when said dial and type-wheel are 5 in proper position to indicate and print one of their numbers.

17. In a cash indicator and recorder, the combination of a casing having a sight-opening, a shaft, an indicating-dial fast upon the 10 shaft and adapted to expose its numbers singly at the sight-opening, an oscillatory screen-plate coöperating with the dial to alternately hide and expose its numbers at the sight-opening, a type-wheel also fast upon the 15 shaft, a platen coöperating therewith, an operating-lever, connections between the same and the screen-plate and platen for actuating them, a notched disk also fast upon the shaft, and a latch or locking device coöperating 20 with said notched disk and with the operating-lever to prevent operation of the latter except when the indicating-dial and type-wheel are in proper indicating and printing positions.

18. The combination of the casing having the sight-opening 6, the shaft 2, the handle 3 and pointer 4 fast thereon, the latter moving over a series of numbers upon the casing, the 25 dial 5 and type-wheel 7 also fast on the shaft 2, paper-strip-feeding mechanism, a platen coöperating with the type-wheel, and means intermediate the handle and platen and feeding mechanism for actuating the platen by the movement of the handle and advancing 30 the paper strip.

19. The combination of the shaft 2, the type-wheel 7 fast thereon, the lever 20 carrying the platen 15 coöperating with the type-wheel, the arm 31 loose upon the shaft 2 and 40 coöperating with the lever 20, the inking-roller 32 carried by the arm 31, the spring 22 for the lever 20, the operating-lever 45, and the trip 26 carried thereby and coöperating with the lever 20, substantially as described.

20. The combination of the casing having the sight-opening 6, the shaft 2, the handle 3 and pointer 4 fast thereon, the latter coöperating with the series of numbers on the casing, the dial 5 and type-wheel 7 fast on the 45 shaft 2, the screen-plate 51 coöperating with the dial, the lever 20, the platen 15 carried thereby and coöperating with the type-wheel, the spring 22, and the lever 45 coöperating with the screen-plate 51 and carrying the trip 26 55 coöperating with the lever 20, substantially as described.

21. In a cash-recorder, the combination of a shaft, a type-carrier moving therewith, a platen coöperating with the type-carrier, a 60 money-drawer, a lock therefor, an operating handle or lever independent of the money-drawer, and connections between said lever and the platen and drawer-lock, for effecting the printing and releasing the drawer by the 65 operation of said lever.

22. In a cash-recorder, the combination of

a shaft, a type-carrier fast theron, a platen coöperating with the type-carrier, means for drawing a record-strip between the platen and type-carrier, an operating-lever, and connections between said platen and record-strip mechanism, for advancing said strip and effecting the printing at the positive stroke of 70 said lever.

23. In a cash-recorder, the combination of 75 a shaft, a type-carrier fast theron, a platen coöperating with said carrier, means for drawing a record-strip between the platen and carrier, an automatically-opening money-drawer, a lock therefor, an operating-lever independent of the money-drawer, and connections between said lever and the platen, record-strip mechanism and drawer-lock, for effecting the printing, advancing the record-strip and unlocking the drawer by the operation 80 of said lever.

24. In a cash-indicator provided with a casing having a sight-opening, the combination of a shaft, an indicating-dial fast thereon and adapted to expose its numbers singly at said 90 sight-opening, a screen-plate movable back and forth between said opening and the indicating-dial, a money-drawer, a lock therefor, an operating-lever, and connections between said lever and the screen-plate and drawer-lock, for moving the screen-plate away from 95 the sight-opening and unlocking the drawer by the operation of said lever.

25. The combination of the shaft 2, the notched disk 41 and type-wheel 7 fast on said 100 shaft, the lever 20 carrying the platen 15 coöperating with the type-wheel, the spring 22, the lever 45 carrying the trip 26 coöperating with the lever 20, and the lever 42^a coöperating with the disk 41 and lever 45, substantially 105 as described.

26. The combination of the shaft 2, dial 5, type-wheel 7, lever 20, platen 15, spring 22, lever 45, trip 26, drawer 3, latch-bar 47, and 110 arm 46 interposed between the lever 45 and latch-bar 47, substantially as described.

27. The combination of the casing having the sight-opening 6, the oscillatory shaft 2, the dial 5 fast thereon, the oscillatory screen-plates 51 and 52, the springs 53 frictionally 115 connecting the plates with the dial, and the lever 45 coöperating with the plate 51, substantially as described.

28. In a cash-recorder, the combination of the ratchet-wheel 8, provided with the storage flange or drum 19, and having the supply-roll of the record-strip carried upon its hub and led thence past the printing-point and wound upon the drum 19, and means for turning the ratchet-wheel, substantially as described. 120 125
